THOMAS H. MATHIAS, OF BUFFALO, NEW YORK, ASSIGNOR TO LACKAWANNA STEEL COMPANY, OF NEW YORK, N. Y., A CORPORATION OF NEW YORK.

PROCESS AND MECHANISM FOR ROLLING SPECIAL SHAPES.

1,176,308.

Specification of Letters Patent. Patented Mar. 21, 1916.

Application filed February 8, 1909. Serial No. 476,703.

To all whom it may concern:

Be it known that I, THOMAS H. MATHIAS, a citizen of the United States, residing at Buffalo, in the county of Erie and State of New York, have invented new and useful Improvements in Processes and Mechanism for Rolling Special Shapes, of which the following is a specification.

My invention relates to a train of rolls formed with a new and improved set of passes, whereby the sections of a new and peculiar steel sheet piling are rolled complete from the billet. The pile sections in question are of the so-called double interlock type and are provided with short thickened flanges or "thumbs" projecting on one side at each end of the web, and with long, tapering, curved flanges called "guards" or "fingers" projecting at each edge on the side opposite to the thumbs and curved outwardly beyond the short flanges, to form with the latter grooves for interlocking along each edge of the section. To roll this section presents a peculiar problem for the rolling mill superintendent and has been successfully accomplished by forming and arranging the rolls as here described, whereby these peculiar sections, with long flanges on one side, may be rolled on comparatively a small train of rolls.

By the first passes the section is roughed into shape, that is, the bloom is rolled down into the H form and the web and extensions thereon worked out; next both extensions on one side are worked out in live passes into the complete flanges, so far as size is concerned, while both the opposite extensions are held in dead passes and there more or less compressed into what we call "bumps," which are the rudimentary parts from which the completed hooks or "thumbs" are formed; next the flanges are held in dead passes while the "bumps" are being formed as to shape and simultaneously bent out as to position into the "thumbs" of the completed section; finally the flanges are bent outwardly in the last pass beyond the hooks to form the completed guards. The pile section is then complete and ready for use as it comes from the rolls. In the last pass it is desirable

that a guide be used to hold the flange in position to be bent outwardly, more or less to inclose the hook. The web is maintained throughout parallel to the axis of the rolls. 55

The drawings herewith illustrate the forms of my rolls and in section the form of the bar as it is progressively shaped.

Figures 1, 2 and 3 are vertical longitudinal sectional views showing respectively the first 60 and second stand of roughing rolls and the stand of finishing rolls. Fig. 4 is a front elevation of the rolls forming the finishing passes, particularly to show the arrangement of the guides. Figs. 5 and 6 are respectively a front elevation and a side elevation with the rolls in section.

Three high rolls as indicated are used and these are comparatively small, a desirable size being about 26 $\frac{1}{4}$ inch pitch diameter for 70 the top and bottom rolls and 27" pitch diameter for the middle roll.

The bloom, preferably of H shape, is first roughed into shape in passes 1 and 2, wherein the bumps a and the opposite flanges b 75 are somewhat worked out and the web thinned. In the next passes 3 and 4, the bumps are held while the flanges are being worked out in live passes. At the same time the flanges are outwardly curved or 80 flared to obtain sufficient length. In pass 5, being the first of the second roughing stand, the bumps are still held, the web is worked down to its final thickness and the flanges are bent substantially parallel and substantially at right angles to the web; the flanges are now complete so far as size is concerned. In the next three passes 6, 7 and 8 the flanges are held unchanged in dead passes, while in the live passes the bumps are being shaped into the hooks or "thumbs" of 90 the completed section. In pass 6 the bumps are bent outwardly; in pass 7, they are maintained substantially in the same position and are shaped to some extent; in pass 8 they 95 are bent somewhat farther into final position and simultaneously their shaping is completed as the finished "thumbs." The section is now finished except that the flanges must be bent outwardly beyond the 100 hooks to form the pockets or grooves. This is done in passes 9 and 10. Pass 9 as shown

is formed to bend outwardly the tips of the flanges while the final pass 10 bends the flanges beyond the hooks and down, as shown to complete the pile section.

- 5 In Figs. 4, 5 and 6 are illustrated guides suitably supported which are desirably employed in connection with each of the passes to present the sections true to the rolls, also mandrels, or mandrel-guides, to coöperate
 10 with the final pass 10 to insure the true and uniform curvature of the flanges in the finished piling. As shown, the side guides 12-12 are spaced to receive between them the section to guide it, whereby it is delivered
 15 at a right angle to the rolls in correct relation to the pass, while upper and lower pass-guides 14 and 15 are arranged to form a guideway for the passage of the section between them to present the section to the passes in correct vertical alinement therewith. The guides are all supported by the
 20 rest-bar 16 arranged to extend across the rolls and parallel thereto; the side-guides 12 rest directly thereon and are securely
 25 clamped in position by bolts 18-18, said bolts passing upwardly through the clamping plates 20 beneath the rest bar, through the side guides and through the upper pass guide supporting plate 21.
 30 22 are the securing nuts on the upper ends of the bolts.

The upper pass guide 14 is secured and supported on the upper supporting plate 21 by the bolts 23, the plate resting as shown
 35 on the side guides 12, while the lower pass-guide is supported directly on the rest bar by suitable bolts 24. It will thus be seen that by loosening the securing nuts 22 the side guides, and the mandrels, supported
 40 thereon and used in connection with the final pass, can be adjusted laterally on the rest-bar relative to the passes.

To assist the final pass 10 in the formation of the curved guards or flanges, it is
 45 found desirable to employ a mandrel 25 preferably tapering as shown and arranged to extend between the rolls of the final pass, to insure the uniform curvature of the flanges; this result being accomplished by
 50 the relative formation of the rolls and mandrel whereby the flanges are bent over the mandrel as best shown in Figs. 5 and 6.

Two mandrels 25 are provided for the formation of the opposite curved flanges, the
 55 mandrels being secured on the side guides by having their rear portions fitted to suitable recesses formed in the guides and by securing bolts 26 fitting slots 27 in the side guides; a vertical adjustment of the mandrels is thus permitted. Rigidly to maintain the mandrels in adjusted position and to relieve the securing bolts thereof from strain spacing wedges 28 may be inserted in the recess above and below the mandrel.

60 In Fig. 4 is illustrated the general ar-

angement of the rolls to form the passes and the relation of the guides thereto, the rolls being journaled in the usual housings 30 provided with bases 31.

It will thus be seen that I have produced
 70 rolls formed to provide a small number of passes essential to the gradual working down of the billet to the finished article and guides arranged relative thereto for the convenient and accurate presenting of the work
 75 to the rolls together with means to insure the uniform curvature of the flanges for the accurate formation of the grooves, which results in a successful solution of the problem presented for the easy and economical
 80 manufacture of a piling obtaining certain advantages by its peculiar formation.

The peculiar rolls here described may be modified and used in whole or in part to produce modified shapes for various purposes.
 85

Having thus described my invention what I claim is,—

1. In an apparatus for rolling interlocking sections of steel sheet-piling having the
 90 edges correspondingly formed each with a short flange and a long flange for interlocking with the flanges on the edge of an adjacent similarly formed section, said short flanges extending on one side of the
 95 section and said long flanges on the other side, rolls provided with suitable passes first to form the long flanges, then to form the short flanges and finally to hold the short flanges and bend the long flanges outwardly
 100 and simultaneously to form grooves for interlocking along both edges of the rolls and in combination therewith mandrel guides to be inserted at the last pass between the rolls from one side and between the flanges at the
 105 edges to control the size and shape of the groove while the long flanges are being bent.

2. The method of rolling interlocking sheet piling sections having long flanges extending on one side of the web and short flanges on the other which consists in passing the bloom between rolls provided with suitable passes to form the long flanges while holding the bumps for the short flanges in dead passes, with other suitable passes next to form the bumps into the short flanges, and with other suitable passes finally to bend the short and the long flanges into position to form grooves for
 110 interlocking along each edge of the completed section.

3. The method of rolling interlocking sheet piling sections having at least one edge of the web formed with a long flange extending on one side of the web and a short flange on the other, which consists in passing the heated bar between rolls provided with suitable passes first to form the long flanges while holding the bumps for the short flanges in dead passes, with other suitable
 115 passes next to form the bumps into the short flanges, and with other suitable passes finally to bend the short and the long flanges into position to form grooves for interlocking along each edge of the completed section.

passes next to form the bumps into the short flanges and to bend them into position, and with other suitable passes next to bend the long flanges outwardly to extend beyond 5 the short flanges and to form grooves for interlocking along each edge of the completed section.

4. The method of rolling from H-shaped billets, interlocking sections for steel sheet piling having long flanges on one side of the web and short flanges or hooks on the other, which consists in passing the heated bar between rolls provided with suitable passes first to work out the flanges on one 10 side of the billet and the bumps on the other side and to thin the web, next to work out and to curve outwardly the flanges while holding the bumps in dead passes, next to straighten the flanges substantially parallel 15 and to reduce the web to its final thickness while holding the bumps in dead passes, next to shape the bumps into the hooks and to bend them into final position while holding the flanges in dead passes, and finally to 20 bend the flanges outwardly with the flange tips extending beyond the hooks to form grooves along each edge of the section for receiving the hooks of adjacent sections.

5. The method of rolling interlocking sections of steel sheet piling having the edges correspondingly provided each with a long flange and a short flange for forming an interlocking groove along each edge, which consists in passing the heated bar between 25 rolls provided with suitable passes first simultaneously to form the long flanges, with other suitable passes next simultaneously to form the short flanges, and with other suitable passes finally to 30 hold the short flanges and to bend the long flanges simultaneously to form the grooves.

6. The method of rolling metal sheet piling sections having the edges of the web correspondingly provided each with a long 45 flange and a short flange for forming an interlocking groove on each edge, which consists in passing the heated bar between rolls provided with suitable passes first simultaneously to form the long flanges, with 50 other suitable passes next simultaneously to form the short flanges, and with other suitable passes finally to bend the long flanges simultaneously to form the grooves, the web of the section being maintained 55 parallel to the axis of the rolls during the entire rolling operation.

7. The method of rolling metal sheet piling sections having the edges of the section web correspondingly formed each with a long flange and a short flange and an interlocking groove within the flanges, which consists in passing the heated bar between rolls provided with suitable passes, first to 60 form the long flanges, next to hold the long flanges substantially parallel and form the

short flanges, and next to bend the long flanges simultaneously away from each other and around toward the short flanges, the web being maintained parallel to the axis of the rolls during the entire operation. 70

8. The method of rolling metal sheet piling sections having on at least one edge of the web a short, thick flange, or thumb, and a long flange, or guard, which consists in passing the heated bar through rolls provided with suitable passes first to form the long flange, next to form the short flange, and finally to hold the short flange and to bend the long flange outwardly to form in coöperation with the thumb a groove, said 75 flanges being held in the final pass by a mandrel guide to be inserted between the rolls from one side to hold the short flanges and to control the bending of the long flange. 80

9. The method of rolling interlocking steel sheet piling sections having two long flanges extending on one side of the web, one adjacent each edge, and two corresponding short flanges extending on the 90 other side, one adjacent each edge, which consists in passing the heated bar through rolls provided with suitable passes first to form the long flanges simultaneously and to hold the rudimentary short flanges in 95 dead passes, next to form the short flanges simultaneously with laterally elongated heads and to hold the long flanges unchanged in dead passes, next to bend the short flanges into position, and finally to 100 bend the long flanges toward the short flanges to form interlocking grooves along the edges of the completed section of sufficient size to receive the heads of the short flanges but with throats narrower than the 105 length of the said heads.

10. A machine for forming interlocking sheet piling sections having both edges similarly formed with long curved flanges extending on one side of the web and short hooked flanges extending on the other, comprising opposing rolls formed with a series of passes, the first series having dead grooves in one roll to hold the bumps for the short flanges, opposing convex portions or collars on the two rolls to engage with and work down the web, and outwardly curved live grooves between the opposing rolls to engage with and work out the long flanges; the next series having dead grooves in one roll for the bumps, opposite collars to work down the web and straight live grooves to work down the long flanges and to bend them substantially straight; the next series having collars for the web, dead grooves in one roll to hold the long flanges unchanged and short live grooves to roll down the bumps into the complete short flanges and to bend said short flanges outwardly; the next series having collars for the web, 110 115 120 125 130

- dead grooves to hold the short flanges unchanged and open grooves opposite said dead grooves to engage with the flange and curve it outwardly, and a final pass having collars for the web, dead grooves to hold the hooks and open "dead" grooves opposite thereto to bend the flanges farther outwardly and downwardly to extend beyond the hooks.
- 10 11. A machine for forming interlocking sheet piling sections having both edges similarly formed with long curved flanges extending on one side of the web and short hooked flanges extending on the other, comprising opposing rolls formed with a series of passes, the first series having dead grooves in one roll to hold the bumps for the two short flanges, opposing convex portions or collars on the two rolls to engage with and work down the web, and outwardly curved live grooves between the opposing rolls to engage with and work out the long flanges; the next series having dead grooves in one roll for the bumps, opposite collars 25 to work down the web and straight live grooves to work down the long flanges and to bend them substantially straight; the next series having collars for the web, dead grooves in one roll to hold the long flanges unchanged and short live grooves to roll 30 down the bumps into the complete short flanges and to bend said short flanges outwardly; the next series having collars for the web, dead grooves to hold the short flanges unchanged and open grooves opposite said dead grooves, said open grooves extending into the roll substantially at right angles to its axis and having two sides, the outer sides being substantially straight and the inner sides curved to engage with 40 the flange and curve it outwardly, and a final pass having collars to engage with the web, dead grooves to hold the hooks and open grooves opposite thereto, the latter grooves being shallower than the preceding 45 grooves and being formed in one curve to bend the long flanges outwardly and downwardly to extend beyond the hooks; the surfaces of the collars in all the passes being substantially parallel to the longitudinal axes of the rolls.

In testimony whereof I have signed my name to this specification in the presence of two subscribing witnesses.

THOMAS H. MATHIAS.
